(57) **CLAIM**

The ornamental design for a base for a painting container, as shown and described.

DESCRIPTION

FIG. 1 shows a perspective view of a base for a painting container.

FIG. 2 shows a top view of the base in FIG. 1.

FIG. 3 shows a bottom view of the base in FIG. 1.

FIG. 4 shows a front view of the base in FIG. 1.

FIG. 5 shows a rear view of the base in FIG. 1.

FIG. 6 shows a left-side view of the base in FIG. 1; and, FIG. 7 shows a right-side view of the lid in FIG. 1.

The portions of the design shown in broken or dotted lines are for illustrative purposes only and form no part of the claimed design.

1 Claim, 7 Drawing Sheets
